US00D645401S

(12) **United States Design Patent**
Kurata

(10) **Patent No.:** **US D645,401 S**
(45) **Date of Patent:** **** Sep. 20, 2011**

(54) **DISPLAY APPARATUS FOR PHOTOVOLTAIC POWER GENERATION**

(75) Inventor: **Masaaki Kurata**, Wako (JP)

(73) Assignee: **Kabushiki Kaisha Toshiba**, Minato-ku, Tokyo (JP)

(**) Term: **14 Years**

(21) Appl. No.: **29/384,972**

(22) Filed: **Feb. 7, 2011**

(51) **LOC (9) Cl.** **13-02**

(52) **U.S. Cl.** **D13/102**

(58) **Field of Classification Search** **D13/102, D13/101, 107, 108, 110, 162, 199; D14/125, D14/299, 371, 374, 455; 126/574; 136/244, 136/245, 251; 320/101**

See application file for complete search history.

(57) **CLAIM**

The ornamental design for a display apparatus for photovoltaic power generation.

DESCRIPTION

FIG. 1 is a front perspective view of a display apparatus for photovoltaic power generation, showing my new design;
FIG. 2 is a rear perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a left side elevational view thereof; and,
FIG. 8 is a right side elevational view thereof.
